UNITED STATES PATENT OFFICE.

RENE E. DUPLESSIS, OF BEVERLY, MASSACHUSETTS, ASSIGNOR TO UNITED SHOE MACHINERY CORPORATION, OF PATERSON, NEW JERSEY, A CORPORATION OF NEW JERSEY.

SHOE-END-CLAMPING MECHANISM.

Application filed May 7, 1920. Serial No. 379,532.

To all whom it may concern:

Be it known that I, RENE E. DUPLESSIS, a citizen of the United States, residing at Beverly, in the county of Essex and State 5 of Massachusetts, have invented certain Improvements in Shoe-End-Clamping Mechanisms, of which the following description, in connection with the accompanying drawings, is a specification, like reference characters on the drawings indicating like parts in the several figures.

This invention relates to machines for use in the manufacture of boots and shoes, and more particularly to mechanism for clamping an end portion of a shoe. The invention is herein illustrated in its application to the heel end clamping mechanism of a bed lasting machine of a well-known type, characteristic features of which are shown 15 and described, for example, in United States Letters Patent No. 1,018,477, granted on February 27, 1912, upon an application of Matthias Brock. It will be evident, however, that while important advantages are 20 involved in the illustrated use of the invention, in many of its aspects the invention is not limited to heel end clamping nor to embodiment in a machine of the particular type herein shown.

In the use of machines of the type illustrated in said prior patent, the shoe on its support is jacked backwardly into a heel embracing band provided for shaping the upper to the contour of the last round the 25 heel end portion and for holding the upper and the last for the operation of the heel wipers, the opposite end portions of the band being closed inwardly against the sides of the shoe after the shoe has been jacked 30 backwardly against the intermediate portion of the band. In machines of this type, as heretofore constructed, conforming and holding pressure of the band against the corners of the end of the shoe as well as its 35 pressure against the extreme end face of the shoe has been dependent for the most part upon the force applied in jacking the shoe backwardly into the band, the yielding means provided for closing the band against 40 the sides of the shoe having comparatively little effect to increase the pressure of the band round the end face of the shoe. In many shoes, however, particularly heavy

shoes in which the upper materials are comparatively stiff and unyielding, it is desirable for the best results in the shaping and holding of the upper materials to apply round the end face of the shoe, and particularly at the corners, a heavier pressure than it is feasible to produce in jacking the shoe 55 back into the open band. An object of this invention accordingly is to provide an improved construction of end clamping means adapted to produce more satisfactory results than heretofore in operating upon comparatively heavy shoes.

With the above and other objects in view, a feature of the invention consists in novel means for applying closing pressure to an end embracing band, so constructed as to produce comparatively heavy pressure of the band round the end face of the shoe. As applied to band closing means of a well-known type comprising closing members mounted for movement lengthwise of the shoe and 60 acted upon in such lengthwise movement by wedging means which forces them inwardly toward the sides of the shoe, the invention in its illustrative embodiment provides connections between the closing members and 65 the end portions of the band constructed to prevent relative yield lengthwise of the shoe between said members and the band in the closing of the band. In such a construction the closing members are caused to act with 70 a substantial forward pull on the ends of the band to tighten it round the corners of the end of the shoe as it is forced inwardly 75 against the sides of the shoe by the determinate lateral movement of said members.

Further to facilitate the application of effective and satisfactory pressure round the end of the shoe, the end embracing band in the machine shown is so mounted as to permit it to be moved bodily lengthwise of the 80 shoe by the forwardly directed force applied to its opposite ends. Such provision for bodily movement of the band permits it to be drawn with comparatively heavy pressure round the entire end face of the shoe. 85 In order, however, to prevent such movement of the band as to apply undue pressure on the extreme end face of the shoe in proportion to the pressure applied at other parts, for example at the corners, and also 90 to guard against displacement of the shoe 95

relatively to the wipers by the pressure of the band, the invention, as a further feature, provides yieldable means for preventing bodily movement of the band except in response to a substantial degree of force applied. In accordance with a further desirable and novel characteristic of the construction shown the yieldable means normally resisting bodily movement of the band is adjustable as to tension to permit variation of the pressure applied at the end of the shoe in accordance with the varying requirements of different shoes.

It will be evident that in the construction shown, in which the band closing members are unyieldingly connected to the ends of the band, their movement lengthwise of the shoe through which they are wedged inwardly also toward the sides is substantially less than in prior constructions having yieldingly swinging lever connections between the members and the band. In view of this condition, and in order to avoid the necessity of an undesirably abrupt action of the wedging means in order to close the band properly, the invention further affords provision for adjustment of the unyielding connections between the closing members and the ends of the band to permit the band to be positioned in such relation to the opposite side faces of each size and style of shoe as to minimize the extent of closing movement of the band required to clamp the work properly at the sides.

The above and other features of the invention, including certain details of construction and combinations of parts, will now be described with reference to the accompanying drawings and pointed out in the claims.

In the drawings:

Fig. 1 is a longitudinal vertical section of the heel lasting portion of a machine of the type illustrated in said prior patent with the novel features of the present invention applied thereto, and

Fig. 2 is a plan view of the heel embracing band and its operating connections.

In common with prior machines of the illustrative type, the machine herein shown comprises a shoe support or jack 2 having a pin to engage in the socket of an inverted last on which are mounted shoe materials ready for lasting, the shoe support 2 being mounted on a carrier 4 which is movable in guideways on a supporting member 6 to force the heel end portion of the shoe lengthwise into the heel clamping band and to position the shoe in operative relation to heel wipers 8. Movement of the carrier 4 to jack the shoe into the band is effected by manual means not shown in detail, but including a pinion 10 engaging rack teeth on the upper face of the carrier. The shoe support 2 is mounted for vertical movement

in the carrier 4 and rests at its lower end upon a pivoted lever 12 provided with a wedge face engaging a screw 14 whereby the support is moved upwardly during its rearward movement with the carrier 4 to position the heel seat in the proper plane relatively to the wipers. It will be understood that at the end of its shoe jacking movement the carrier 4 is locked against retractive movement by suitable retaining means as illustrated, for example, in said prior patent.

The heel embracing or clamping band comprises a flexible member 16 which may be made of any suitable material, and for the purposes of the present invention preferably comprises a pad of comparatively yieldable material such as balata gum, and an outer enclosing or backing member 18 which, as shown, may comprise a chain with a series of links extending round the end of the shoe from one side portion to the other. For closing the opposite end portions of the band inwardly against the sides of the heel end of the shoe the machine herein shown, as in prior constructions, has a cam 20 which may be operated as heretofore by power under the control of a suitable clutch, this cam acting upon a roll 22 on a lever 24 connected by means of a bar 26 to a pivotally mounted lever 28, the bar 26 comprising parts relatively movable to permit lateral adjustment of the heel lasting mechanism. At its rear end the lever 28 engages the lower end of a lever 30 which is connected by a comparatively heavy spring 32 to a slidably mounted block 34. Extending from the block 34 is a rod 36 on the front end of which is pivotally mounted a closing bar 38 connected by links 40 to forwardly extending bars or slides 42 which serve as closing members for the band, these slides being guided at their rear ends in slots formed in a portion 44 of the heel lasting head. At their front ends the members 42 are connected to the ends of the band chain 18 by arms 46 provided with slots 48 to receive pins 50 projecting upwardly from the members 42. The pins 50 thus serve to hold the arms 46 rigidly against yielding movement relatively to the members 42 as these members are moved forwardly by their operating means. Further to determine the position of the arms 46 on the members 42, the latter are provided with rods 52 which are suitably secured thereto and are threaded to receive nuts 54 having flanges 56 to engage in slots in the arms 46, whereby the arms may be adjusted laterally of the members 42 and held in adjusted position.

As the closing members 42 are moved forwardly by the operating means described, they are swung inwardly about their rear ends toward the sides of the shoe to close

the ends of the band against the shoe by the wedging action of pins 58 engaging in curved slots 60 in the closing members. It will thus be evident that in the operation 5 of the band closing means through the tension of the comparatively heavy spring 32 the ends of the band are closed inwardly against the sides of the shoe by the lateral movement of the members 42 and that at 10 the same time, by reason of the unyielding connections between the ends of the band and the closing members, a substantial forward pull is applied to the ends of the band to draw it with increased pressure 15 round the corners of the heel end face of the shoe where, as is well-known, the shaping of upper materials including an end stiffener or counter is particularly difficult.

By adjustment of the nuts 54 the band 20 closing means may be readily conditioned to apply, on different sizes and styles of shoes, the requisite degree of pressure at the sides in proportion to that applied round the end of the shoe, comparatively less pressure, of course, being required to shape the upper at the sides. Such adjustment also minimizes the extent of lengthwise movement of the slides 42 required for properly closing the band. When the arms 46 have 25 been adjusted in accordance with the requirements of any particular size and style of shoe, no further adjustment is required in operating upon different shoes of the same size and style. It will be understood 30 that the yielding character of the material of which the inner shoe-engaging portion 35 of the band is formed, particularly if material such as balata gum is used, is adapted to compensate for any slight differences in the thickness of the upper materials 40 of different shoes without the necessity for adjustment of the band.

At its intermediate portion, at the extreme rear end of the shoe, the band is supported 45 on a cross bar or yoke 62 adjustably mounted and controlled by a hand wheel 64 to permit lateral adjustment of the band in a manner similar to the construction shown and described in United States Letters Patent No. 1,306,247, granted on June 10, 1919 upon an application of Matthias Brock. For purposes of this invention the supporting yoke 62 is mounted for movement lengthwise of the shoe, the yoke being guided by 55 slots 66 in the heel lasting head in co-operation with rolls 68 which are mounted in the slots and have pins 70 engaging in transverse slots in the ends of the yoke member to permit the adjustment of this member as 60 above described. Such provision for forward movement of the supporting member 62 permits the band to be drawn still more firmly against the extreme end face as well as the corners of the end of the shoe by the 65 forward pull of the closing members on the

ends of the band. In order, however, to avoid a disproportionate degree of pressure against the extreme end face of the shoe by the forward pull on the ends of the band and by such tendency as the members 42 70 have to force the yoke member 62 forwardly through their pressure on the pins 58 which are mounted on the yoke member, the machine is further provided with yielding means to prevent forward movement of the 75 yoke member except in response to a substantial degree of force applied to the ends of the band acting to tighten it against the corners of the end of the shoe. For this purpose a rod 72 is slidably mounted in the 80 heel lasting head and is connected at its front end to a block 74 dovetailed in a transverse slideway in the yoke member 62 to permit the adjusting movement of this member laterally of the shoe, the rod having mounted thereon a spring 76 which bears at one end on a portion of the heel lasting head and at its opposite end upon a collar 78 secured on the rod. With this construction 85 forward movement of the band as a whole 90 can take place only against the resistance of the spring 76, the force of the latter being such as to avoid disproportionate or undesirable forward pressure of the band against the extreme end face of the shoe. The collar 95 90 may be fixed by means of a screw 80 in different adjusted positions on the rod 72 to vary as desired the pressure of the spring 76 in accordance with the requirements of the character of the work upon which the 100 machine is to operate.

Since the purpose and the manner of operation of the different parts and the sequence of the different operations have been fully set forth in the foregoing description, 105 no further description of the operation of the machine is necessary for an understanding of the invention.

Having described the invention, what I claim as new and desire to secure by Letters Patent of the United States is:

1. In mechanism of the class described, the combination with shoe positioning means, of a band for embracing an end of the shoe, band closing members movable lengthwise 110 of the shoe at its opposite sides to close the band about the end of the shoe, said members being so connected to the band as to prevent relative movement lengthwise of the shoe between them and the band in the closing of the band, and means operative in response to the movement of said members lengthwise of the shoe to force them inwardly toward the sides of the shoe.

2. In mechanism of the class described, the combination with shoe positioning means, of a band for embracing an end of the shoe, band closing bars extending lengthwise along the opposite sides of the shoe and movable lengthwise to close the band about 115 120 125 130

the end of the shoe, connections between said bars and the end portions of the band constructed to prevent relative movement between the bars and the end portions of the band both lengthwise and laterally of the shoe in the closing of the band about the shoe, and means operative in response to the lengthwise movement of said bars to force them inwardly toward the sides of the shoe.

3. In mechanism of the class described, the combination with a shoe support, of a band for embracing an end of the shoe, band closing members mounted for operative movement lengthwise of the shoe and connected respectively to the opposite ends of the band, and mechanism arranged to act in response to said movement of the closing members and independently of the resistance of the shoe to move said members laterally of the shoe and force the band against the sides of the shoe, the connections between said members and the ends of the band being constructed to prevent relative movement between the members and the band lengthwise of the shoe to cause said members to draw the band tightly round the end of the shoe.

4. In mechanism of the class described, the combination with a shoe support, of a band for embracing an end of the shoe, band closing members mounted for operative movement lengthwise of the shoe, wedge mechanism arranged to act in response to said movement of the closing members to impart to said members a proportional movement toward the sides of the shoe, and connections between said members and the ends of the band constructed to prevent relative movement lengthwise of the shoe between the members and the band in the closing of the band.

5. In mechanism of the class described, the combination with a shoe support, of a band for embracing an end of the shoe, band closing members mounted for operative movement lengthwise of the shoe, wedge mechanism arranged to act in response to said movement of the closing members to swing them about their rear ends toward the sides of the shoe, and connections between the front ends of said members and the ends of the band constructed to prevent relative yield between the members and the band in the closing of the band.

6. In mechanism of the class described, the combination with a shoe support, of a band for embracing an end of the shoe, band closing slides mounted for operative movement lengthwise of the shoe, wedge mechanism responsive to said movement of the slides to force them inwardly toward the sides of the shoe, and connecting members extending across from said slides to the band and pivotally connected to the ends of the band, said

members being rigid with the slides against the band closing force applied by the slides lengthwise of the shoe.

7. In mechanism of the class described, the combination with a heel end embracing band and a shoe support movable to force the heel end of a shoe into said band, of band closing members operatively movable lengthwise of the shoe, wedging means responsive to said movement of the closing members to force them inwardly toward the sides of the shoe for closing the band against the shoe, and connections between said members and the end portions of the band constructed to transmit the force of the members unyieldingly to the band in a direction lengthwise of the shoe for tightening the band round the end face of the shoe.

8. In mechanism of the class described, the combination with a shoe support, of a band for embracing an end of the shoe, band closing members mounted for operative movement lengthwise of the shoe, wedging means for imparting to said members a component of movement laterally of the shoe in proportion to their lengthwise movement, connections between said members and the opposite end portions of the band constructed to prevent relative yield between the band and said members both lengthwise and laterally of the shoe, and means for effecting preliminary adjustment laterally of the shoe of the opposite end portions of the band.

9. In mechanism of the class described, the combination with a shoe support, of a band for embracing an end of the shoe, band closing members mounted for operative movement lengthwise of the shoe, wedging means for imparting to said members a component of movement laterally of the shoe in proportion to their lengthwise movement, and unyielding connections between said members and the opposite end portions of the band constructed to permit relative adjustment between the band and said members.

10. In mechanism of the class described, the combination with a shoe support, of a band for embracing an end of the shoe, band closing members mounted for operative movement lengthwise of the shoe, mechanism for effecting a proportional movement of said members laterally of the shoe in their lengthwise movement, and connecting arms extending across from said members to the end portions of the band, said arms being rigid with the closing members against the band closing force applied by said members lengthwise of the shoe and adjustable relatively to said members laterally of the shoe.

11. In mechanism of the class described, the combination with a shoe support, of a band for embracing an end of the shoe, band closing slides mounted for operative move-

ment lengthwise of the shoe, wedge mechanism to force said slides inwardly toward the sides of the shoe in their lengthwise movement, members rigid with said slides 5 and pivoted to the ends of the band to connect the slides to the band, and threaded connections for adjusting said members laterally of the shoe and relatively to the slides.

10 12. In mechanism of the class described, the combination with a shoe support, of a band for embracing an end of the shoe, band closing members operatively movable lengthwise of the shoe, wedging means responsive to said movement of the closing members to force them inwardly toward the sides of the shoe, connections between said members and the opposite end portions of the band constructed to prevent relative 15 movement between said members and the band in a direction lengthwise of the shoe in the closing of the band, and supporting means for the intermediate portion of the band constructed to permit the band to be 20 moved bodily lengthwise of the shoe by the force of said closing members.

13. In mechanism of the class described, the combination with a shoe support, of a band for embracing an end of the shoe, band 30 closing members connected unyieldingly to the opposite end portions of said band and mounted for operative movement lengthwise of the shoe with a component of movement laterally of the shoe in proportion to their 35 lengthwise movement, said band being mounted for bodily movement lengthwise of the shoe in response to the force applied by said members, and yieldable means for preventing such bodily movement of the band 40 until a determinate degree of said force is exceeded to prevent undue pressure of the band against the extreme end of the shoe.

14. In mechanism of the class described, the combination with a shoe support, of a 45 band for embracing an end of the shoe, closing members movable lengthwise of the shoe with a component of movement laterally of the shoe in proportion to their lengthwise movement to draw the band 50 round the end and close it against the sides of the shoe, connections between said members and the ends of the band constructed to prevent relative movement between said members and the band lengthwise of the 55 shoe in the closing of the band, and yielding means connected to the intermediate portion of the band to permit said intermediate portion to move lengthwise of the shoe only when a determinate force applied at 60 the ends of the band is exceeded.

15. In mechanism of the class described, the combination with a shoe support, of a band for embracing the heel end of the shoe, band closing members operatively movable lengthwise of the shoe, wedging means re-

sponsive to said movement of the closing members to force them inwardly toward the sides of the shoe, connections between said members and the opposite end portions of the band constructed to transmit the force 70 of said members unyieldingly to the band in a direction lengthwise of the shoe, and supporting means for the intermediate portion of the band including a spring yieldable to permit bodily movement of the band lengthwise of the shoe in response to the force of 75 said closing members.

16. In mechanism of the class described, the combination with a heel end embracing band and a shoe support movable to force 80 the heel end of a shoe into said band, of band closing means unyieldingly connected to the opposite ends of said band to force it inwardly against the sides of the shoe and tighten it round the end of the shoe, supporting means for the intermediate portion of the band constructed to permit bodily movement of the band lengthwise of the shoe in response to the force applied at its 85 ends, and spring means for preventing such bodily movement of the band until the band has been drawn tightly against the corners 90 of the end of the shoe.

17. In mechanism of the class described, the combination with a shoe support, of a 95 band for embracing an end of the shoe, closing members connected to the opposite ends of the band and mounted for operative movement lengthwise of the shoe, a support for the intermediate portion of the band 100 also mounted for movement lengthwise of the shoe, wedging means acting between said support and closing members to force said members inward laterally of the shoe in response to their movement lengthwise of the shoe, and spring means arranged to permit movement of said support and band 105 lengthwise of the shoe only in response to a determinate degree of force of said closing members.

18. In mechanism of the class described, the combination with a shoe support, of a band for embracing an end of the shoe, band closing means unyieldingly connected to the opposite ends of the band to draw the band 115 firmly round the corners of the end of the shoe by force directed lengthwise of the shoe, said band being mounted for bodily movement lengthwise of the shoe, and spring means for preventing such bodily 120 movement of the band except in response to a determinate degree of force applied to the ends of the band, said spring means being adjustable as to tension to vary proportionately the relative pressures applied on the 125 extreme end and on the corners of the end of the shoe.

19. In mechanism of the class described, the combination with a shoe support, of a band for embracing an end of the shoe, band 130

- closing means movable lengthwise of the shoe to draw the band round the end of the shoe, connections for transmitting the force of said closing means unyieldingly to the 5 band in a direction lengthwise of the shoe, and spring means connected to the intermediate portion of the band to permit said intermediate portion to move lengthwise of the shoe only in response to a predetermined 10 force applied at the ends of the band, said spring means being adjustable as to tension to vary the degree of force required to cause bodily movement of the band lengthwise of the shoe.
- 15 20. In mechanism of the class described, the combination with a shoe support, of a band for embracing an end of the shoe, closing members mounted for movement lengthwise of the shoe with a component of movement laterally of the shoe and unyieldingly connected to the ends of the band to draw the band round the end of the shoe and force it against the sides of the shoe, a support 20 for the intermediate portion of the band 25 mounted for movement lengthwise of the shoe, a spring normally acting to resist said movement of the support, and means for adjusting the tension of said spring.
21. In mechanism of the class described, 30 the combination with shoe positioning

means, of a band for embracing an end of the shoe, closing bars movable lengthwise of the shoe at the opposite sides of the shoe, wedging means automatically operative in the movement of said bars lengthwise of the 35 shoe to force them inwardly toward the sides of the shoe, and arms extending transversely of said bars and connected to the ends of the band, said arms being rigid with the bars against the band closing force applied by the bars lengthwise of the shoe.

22. In mechanism of the class described, the combination with shoe positioning means, of a band for embracing an end of the shoe, closing bars movable lengthwise of the shoe 45 at the opposite sides of the shoe, means automatically operative in the movement of said bars lengthwise of the shoe to force them inwardly toward the sides of the shoe, arms extending transversely of said bars and connected to the ends of the band, said arms being rigid with the bars against the band closing force applied by the bars both lengthwise and laterally of the shoe, and connections permitting adjustment of said 50 arms relatively to the bars in directions laterally of the shoe.

In testimony whereof I have signed my name to this specification.

RENÉ E. DUPLESSIS.
